FIG. 1

FIG. 4

FIG. 2

FIG. 3

FIG. 1 is a perspective view of a single bowl sink embodying my new design;

FIG. 2 is a top plan view thereof;

FIG. 3 is a cross-sectional view thereof taken along the lines 3-3 of FIG. 2; and

FIG. 4 is a cross-sectional view thereof taken along the lines 4-4 of FIG. 2.

The fragmentary broken line representation of a cabinet and the broken line representation of plumbing fixtures in FIG. 1 are for purposes of illustration only.

The characteristic feature of my design resides in the specific configuration of the flange extending from the bowl to the peripheral edge.

I claim:

The ornamental design for a single bowl sink, substantially as shown and described.
